UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

POSITIONING DEVICE FOR RAILWAY-CAR COUPLERS.

Application filed April 19, 1926. Serial No. 103,049.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range."

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the number of broken knuckles and guard arms

on couplers which members are frequently bent or broken when the couplers are not within coupling range. Such devices also reduce the number of accidents to trainmen as they are not required to go between the cars and position the coupler preparatory to coupling.

It has been found advantageous to have the coupler support cast integral with the striking casting to obtain a four sided member which reinforces the end sill, draft sill and associated parts and my device is especially adaptable to such a combined casting.

One or more eccentric rollers or eccentric rockers are frequently placed between the coupler and its support or between the coupler carriage and its support, as the case may be, which devices raise the coupler as they roll or rock to one side, thus causing the coupler to return to central normal position by gravity. Such devices also cause the coupler to move laterally when the car is on a curved track. When a single roller or rocker is used it does not stabilize the coupler, that is, prevent it from revolving around its own longitudinal axis, therefore, a pair of such eccentric members are desirable to act like a parallelogram to raise the coupler (or carriage) in a horizontal plane.

An object of my invention is to tie two (or more) such eccentric members together so as to obtain a unitary and simultaneous action between them to assure a proper operative relation between the positioning device and its associated car parts at all times and under all service conditions.

In the drawings:

Fig. 1 shows a typical application of the device to a railway car.

Fig. 2 is a section on line 2—2 of Fig. 1.

Figs. 3 and 4 are diagrams showing the preferred form in normal position and extreme lateral position, respectively.

Figs. 5 and 6 show the relation of a roller and the connecting links.

Figs. 7 and 8 show a modified form and a different means of retaining the parts in proper relation.

Figs. 9, 10 and 11 show the relation of a rocker and the connecting link.

Figs. 12 and 13 show a modified construction wherein the carriage has been eliminated.

The striking casting or buffer block 2 is

attached to the draft sill 3 or other part of the car in any suitable manner and the coupler support 4 is attached to it or preferably cast integral therewith. The coupler 5 rests upon a carriage 6 which engages the support in such a manner as to restrict its movement longitudinally of the car but permits its movement sidewise of the car. This is preferably accomplished by providing a U-shaped support having spaced apart walls 7-8 between which the carriage moves in one direction but is restricted in its movement longitudinally of the car.

Two (or more) rollers 12 are interposed between the coupler support and the carriage, each of which rollers has a curved upper surface 13 and a lower surface 14 which have a rolling engagement with the carriage and support, respectively. These rollers are held in place by being positioned within a U-shaped support, 4. The radius 15 of each of the curved surfaces is greater than half the depth of the roller so that as it rolls to one side it raises the coupler, as shown in Fig. 4. This is what is called an eccentric roller.

The two rollers are connected by a pair of links 30 which are pivotally connected to both rollers by pin 31. In this form the rollers comprise oppositely disposed wide bearings 32-33 connected by a narrow shank 34 and the links are positioned on opposite sides of the shank. The upper and lower bearings are wider than the overall dimension of the pin (as shown in Fig. 6) so that the device may be positioned within the U-shaped support and move freely therein. The carriage is provided with oppositely disposed projections 17 which engage the outer sides of the rollers and the support is provided with oppositely disposed projections 16 which also engage the outer sides of the rollers. When the coupler moves laterally some of these lugs engage rollers causing them to raise the coupler, which action is shown in Fig. 4.

Figs. 7 and 8 show a similar construction to that described for Figs. 3 and 4 but rockers (35) have been shown instead of rollers (12) and also a single link 36 is shown which is positioned between the spaced apart walls of the rocker and pivotally secured thereto by the pin 37. Furthermore, the support and carriage are each provided with a lug (18 and 19) which is positioned between the rockers and engage the inner sides thereof. Upon a lateral movement of the coupler the lug on the support engages the inner side of one rocker and the lug on the carriage engages the inner side of the other rocker causing them to raise the coupler, which action is shown in Fig. 8.

Figs. 12 and 13 show a constriction similar to that shown in Figs. 3 and 4 except the carriage has been omitted and each of the rollers is provided with a horn 38 which engages one side of the coupler and the coupler support is provided with a projection 18 engaging the inner sides of the respective rollers. The action of this device upon lateral movement of the coupler is shown in Fig. 13. The rollers are connected by the link 39.

In my co-pending application I have claimed a positioning device having eccentric rollers with curved surfaces engaging associated parts of the car but the invention as claimed in this application is an improvement upon such rollers and consists in the use of a pair of such rollers and tying them together for simultaneous operation. When a pair of rollers is used the weight of a coupler may momentarily shift entirely to one roller, thus relieving the other roller of all pressure and permitting it to return to its normal central position or to assume any other position into which the movement of the car might throw it. Such a condition is prevented by tying the rollers together, as disclosed and claimed in this application.

I claim:

1. In a railway car; the combination of a coupler support, a coupler carriage having means to restrict the lateral movement of the coupler relative thereto, a pair of rollers interposed therebetween having curved surfaces engaging, respectively, said support and said carriage, the radius of each surface being greater than half the depth of the rollers, said support and said carriage, respectively, provided with means which engage the rollers upon lateral movement of the coupler, and a link connecting the rollers for simultaneous movement.

2. A centering device for a railway car comprising a pair of rollers connected by a pair of links, each of said rollers having oppositely disposed wide bearings connected by a narrow shank, said links being positioned on opposite sides of the shank, and means to pivotally secure the links to the shanks.

3. A centering device for a railway car coupler comprising a pair of rollers connected by a pair of links, each of said rollers having oppositely disposed wide bearings connected by a narrow shank, said links being positioned on opposite sides of the shank, and means to pivotally secure the links to the shanks, said parts so proportioned that the overall width of the shank, links and means is less than the width of the bearings.

GARTH G. GILPIN.
